UNITED STATES PATENT OFFICE

ALBERT SÉROR, OF CHICAGO, ILLINOIS

DESIGN FOR A DOLL

Application filed March 5, 1931. Serial No. 38,936. Term of patent 3½ years.

To all whom it may concern:

Be it known that I, ALBERT SÉROR, a citizen of the United States and a resident of Chicago, in the county of Cook and State of Illinois, have invented a new, original, and ornamental Design for Doll, of which the following is a specification, reference being had to the accompanying drawing, forming part thereof.

The figure is a perspective view of a doll, showing my new design.

I claim:

The ornamental design for a doll, substantially as shown.

In witness that I claim the foregoing as my invention, I have hereunto affixed my signature this 3rd day of March, 1931.

ALBERT SÉROR.
